UNITED STATES PATENT OFFICE.

JOHN RANDOLF ELLIOTT, OF CLINTON, MISSOURI, ASSIGNOR OF ONE-HALF
TO WILLIAM I. A. BODINE, OF SAME PLACE.

WASHING-MACHINE.

SPECIFICATION forming part of Letters Patent No. 381,003, dated April 10, 1888.

Application filed November 10, 1887. Serial No. 234,815. (No model.)

To all whom it may concern:

Be it known that I, JOHN RANDOLF ELLIOTT, a citizen of the United States, residing at Clinton, in the county of Henry and State of Missouri, have invented a new and useful Improvement in Washing-Machines, of which the following is a specification.

My invention relates to washing-machines; and it consists in certain novel features hereinafter described and claimed.

In the accompanying drawings, which fully illustrate my invention, Figure 1 is a perspective of my improved washing-machine with the cover removed. Fig. 2 is a central longitudinal section of the machine. Fig. 3 is a transverse section of the same on the line xx of Fig. 2, looking in the direction indicated by the arrow; and Fig. 4 is a plan view of the boiler with the cover and cylinder removed.

Referring to the drawings by letter, A designates the boiler, which may be of any desired size and is preferably oblong in shape, and is provided with the usual handles, $a a$. In one end of the boiler I construct a steam-chest, B, which extends nearly to the top of the boiler, as shown, and is provided with the feed-pipe C, having a screw-threaded closure or cap, D, and a discharge-spout, E, which extends inward and slightly upward, so as to direct the steam from the steam-chest onto the clothes in the cylinder F. This cylinder F consists of the circular disks G, having their edges bent slightly inward, and the rubbers or rubbing-bars H, secured to said inwardly-bent edges.

The disks G are each provided with trunnions I I, which rest in bearings in the upper edges of the boiler, and one of these trunnions is extended and bent to provide an operating crank-handle, J. The disks G are further divided to one side of their centers, so as to provide the lid K. The meeting edges of the lid and the main portion L of the disks are provided with the inwardly-projecting flanges M, which provide a firm bearing for the lid when closed.

The lid is hinged to one side of the main portion of the cylinder, as shown, and on the opposite side it is provided with two spring-catches, N, which take over the lugs O on the main portion of the cylinder and thereby secure the lid firmly to its place. The rubbing-

bars are V-shaped in cross-section, as clearly shown, the angle of the V extending inward, so that when the cylinder is revolved the clothes will be forced against the same, as will be presently more particularly referred to. 55

Beneath the cylinder and above the bottom of the boiler I secure the plate P, having a series of openings therein, whereby a perforated false bottom is provided for the boiler. A pipe, Q, having a screw-cap, R, is arranged 60 in one corner of the boiler and leads to the space between the true and false bottoms of the boiler, so as to facilitate the cleaning of the same.

S designates the usual semi-cylinder cover 65 for the machine, having the ordinary handles, T, and provided in its side edges with the notches U, which fit over the trunnions of the cylinder. In order that lateral movement of the cylinder may be prevented, I provide the 70 said trunnions with the annular stops V, which contact with the inner faces of the sides of the boiler, and thereby hold the cylinder to its place.

In practice the steam-chest is filled or nearly 75 filled with water, and water is also poured in the boiler until the perforated bottom is covered therewith. A small quantity of soap is then placed in the water in the boiler, and the clothes, previously soaked in soap and water, are placed in the cylinder. The boiler is placed on a stove or furnace, and when the water is boiling and forming steam in the steam-chest the cylinder is placed in position, the cover applied, and the cylinder slowly 80 revolved. As the cylinder revolves, the clothes therein will be forced against the rubbing-bars and through the boiling water in the boiler, and thus rapidly cleansed. This action is accelerated by the steam from the steam-chest, 85 which is forced directly upon the clothes, thereby removing the dirt therefrom. The sediment from the clothes will be collected in the space between the true and false bottoms of the boiler, and the water above the false bottom thus kept practically clean during the 90 operation of washing. When the washing is completed, the cylinder is removed and the clothes taken therefrom, as will be readily understood. The cleansing of the machine is 95 100

greatly facilitated by the provision of the pipes Q and C, as by inverting the boiler the water used in washing will be discharged through said pipes, and clean water may be poured 5 through the same to cleanse the boiler.

It will be observed that the construction of my device is such that the dirty water in the boiler cannot enter the steam-chest, and consequently only clean water is discharged from 10 the chest through the pipe E onto the cylinder.

My machine is simple in construction and efficient in operation, and its advantages will be readily appreciated.

Having thus described my invention, what I 15 claim, and desire to secure by Letters Patent, is—

A boiler for washing-machines, having a steam-chest in one end provided with a feed-pipe and a discharge-pipe, and a perforated false bottom extending from the steam-chest 20 to the other end of the boiler, substantially as specified.

In testimony that I claim the foregoing as my own I have hereto affixed my signature in presence of two witnesses.

JOHN RANDOLF ELLIOTT.
